UNITED STATES PATENT OFFICE

HERMAN J. TIETZ, OF SAN PEDRO, CALIFORNIA

DESIGN FOR A PORTABLE ELECTRIC COOKER

Application filed January 4, 1932. Serial No. 42,362. Term of patent 14 years.

To all whom it may concern:

Be it known that I, HERMAN J. TIETZ, a citizen of the United States, residing in San Pedro, in the county of Los Angeles and State of California, have invented a new, original, and ornamental Design for a Portable Electric Cooker, of which the following is a specification, reference being had to the accompanying drawing, forming a part thereof.

Fig. 1 is a perspective view of the article showing my new design, and

Fig. 2 is an end view thereof.

The dominant features of my new design are the general outline of the top, including the knob, the side and end ornamentation, and the shape of the legs or supports therefor.

I claim:

The ornamental design for a portable electric cooker, substantially as shown and described.

In testimony whereof I have signed my name to this specification.

HERMAN J. TIETZ.
